DESIGN FOR A SIGN

Joseph D. Zinke, Glendale, Calif.

Application May 17, 1937, Serial No. 69,388

Term of patent 14 years

To all whom it may concern:

Be it known that I, Joseph D. Zinke, a citizen of the United States, residing at the city of Glendale, county of Los Angeles, State of California, have invented a new, original, and ornamental Design for a Sign, of which the following is a specification, reference being had to the accompanying drawing, forming part thereof.

Fig. 1 is a front elevation of the sign embodying my invention, and Fig. 2 is a side elevation of the same.

I claim:

The ornamental design for a sign, substantially as shown.

JOSEPH D. ZINKE.
